Attorney

UNITED STATES PATENT OFFICE.

HENRI BÉNIT, OF PARIS, FRANCE.

DRIVING MECHANISM FOR WINDERS FOR ARTIFICIAL SILK

Application filed July 19, 1926, Serial No. 123,532, and in Germany February 1, 1926.

The difficulties which occur in driving electrically various apparatus used in the manufacture of artificial silk are well known.

The individual control of the centrifugal machines in particular has been effected even quite recently by means of mechanical transmission devices such as toothed gearing, belts etc., which do not permit of obtaining with ease the very high speeds which are necessary in this industry and even when a direct drive is employed, the electrical motors or the essential parts thereof are very rapidly put out of order.

With these considerations in view, a solution has been offered, which without doubt permits spinning boxes to function, but these proposals are too complicated for reliable operation and are further expensive because of the complications which they involve.

It is known that spinning boxes or centrifugal machines into which the thread or artificial silk falls rest on a shaft of appropriate form to which the rotor of an electric motor is directly keyed. The centrifugal machines rotate at a speed of 5000 to 6000 revolutions per minute, and it is therefore indispensable that this shaft, considering its unsupported outer end on one hand and the mass of the spinning box on the other hand, should not be subjected to any deviation about its axis, and if such a deviation should occur that the shaft should automatically centre itself and take its normal position. The difficulty of the problem may thus be realized, especially if it is further considered that it is not possible to make perfectly balanced spinning boxes or pots.

The present invention has for its object driving means including two concentric shafts of which the outer drives by friction the inner one carrying the centrifugal machine or spinning box which avoid the defects mentioned above and above all prevent fracture of the shaft at the critical speeds.

The invention will be understood by reference to the accompanying drawing which by way of example illustrates only one embodiment of the invention.

In the particular case of a winder for which the motor is especially constructed, the latter comprises:

(a) A stator of an asynchronous motor formed by the frame 1 and discs 2. The windings are not shown in order to avoid complicating the drawing. On the frame 1

rests the upper housing 3. The inner circular face of the lower housing 4 serves to support the motor. It is this housing which is adapted for the support of the whole as 60 hereinafter explained.

(b) A rotor of an asynchronous cage motor (the particular case considered being a winder). The discs 5 are forced over a main hollow shaft 6. On the upper part of this main shaft is fixed the box 7 in which is mounted the outer cage of a ball bearing 8, the inner cage being slidably mounted on the sleeve 9 of the upper housing 3 in order to permit expansion of the shaft when the 70 motor attains its normal working temperature. To the lower part of this main shaft is secured a thrust ball bearing 10. This bearing supports the weight of the movable assembly. 75

Within the main shaft 6 is provided a second shaft 11 which is flexible. This inner shaft 11 contacts with the main shaft 6 through the medium of two collars having external spherical surfaces 12-12'. These 80 two collars contact with the main shaft in the axes of the ball bearings 8 and 10. The part between the collars is of reduced diameter so that it is rendered flexible and can consequently become deformed without 85 danger.

The upper part of this flexible shaft extending beyond the main shaft 6 is of greater diameter to provide greater rigidity. This end of the inner shaft 11 is coupled 90 to the device to be driven, in the present case, the spinning box 18.

The rotation of the main shaft 6 is transmitted to the inner shaft 11 by the pressure on the ends of the main shaft of a washer 95 13 and of a cap 14 slidable on the inner shaft 11.

The centre of the radius of curvature of the cap 14 and of the end of the main shaft 6 is located at the intersection of the axis 100 of the upper collar 12 with the axis of the flexible shaft 11.

The contact pressure is regulated by means of a spring 15 through the medium of a nut 16 which is locked after regulation of the 105 pressure, in order to avoid loosening of parts. The assembly is protected by a hood 17.

This arrangement of concentric shafts allows of the employment of high speeds of 110 rotation. The flexible shaft centres itself automatically, the deformation being ren-

dered possible by the reduction of the diameter of the shaft between the collars. The cap 14 at the upper part of the shaft acts in the manner of a shock absorber, completing the elastic system.

8 The mounting of the upper ball bearing in the box 7 assures perfect lubrication and tightness.

10 In the electrical winder described above, the inner flexible shaft has a conical end on which the winding box is placed.

15 It will be understood that the invention is not limited to the example which has been illustrated and described and that the system of driving a body by means of two concentric shafts as described above is to be regarded as lying within the scope of the invention.

20 The present arrangement for driving the inner shaft by friction may be employed in all high speed electric motors having a ver-

tical axis in which the outer end of the shaft extends considerably beyond the outer bearing.

Having thus fully described the invention, 25 what I claim as new and desire to protect by Letters Patent is:

20 A driving system of the character described comprising an outer and an inner shaft, means for driving said outer shaft, 30 collars formed on said inner shaft and engaging the outer shaft, said inner shaft being reduced in diameter and rendered flexible between said collars whereby the inner shaft is centred automatically at high speed, 35 a housing enclosing the said shafts, and ball bearings between the said outer shaft and housing and disposed in the axes of said collars.

40 In witness whereof I have hereunto set my hand.

HENRI BENIT.
